UNITED STATES PATENT OFFICE.

CHARLES M. BREHM, OF DAYTON, OHIO.

TRIMMING MACHINE.

1,420,469.

Specification of Letters Patent. Patented June 20, 1922.

Application filed January 8, 1921. Serial No. 435,976.

To all whom it may concern:

Be it known that I, CHARLES M. BREHM, a citizen of the United States, residing at Dayton, in the county of Montgomery and State 5 of Ohio, have invented certain new and useful Improvements in Trimming Machines, of which the following is a specification, reference being had therein to the accompanying drawing.

10 My invention relates to mechanism for trimming blanks and in particular to a punch and die construction for this purpose.

My object is to provide a mechanism for holding a blank in position despite the relative movement of the punch and die during 15 a trimming operation when a portion of the blank is being trimmed.

Another object is to provide a means of holding the blank while the trimming is 20 taking place and there is not only a lateral movement but a vertical movement of the respective parts of the trimming mechanism.

Referring to the drawings:

Fig. 1 is a section of a die and punch with 25 a blank in position just prior to being trimmed;

Fig. 2 is a sectional view somewhat enlarged of one-half of the blank showing a portion of the top just severed as the result 30 of the trimming operation. The particular blank in this instance is a cup-shaped member which is to be trimmed to form a cylinder.

In the drawings, 1 is the supporting member 35 for a punch which has fastened to it by the pins 2-2, a cam plate 3 with a cam surface 4. This cam plate with its cam surface 4 engages with a co-operating member 5 that has a cam surface 6. The movement of these 40 cam surfaces over one another results in 5 being shifted laterally together with the punch 7. The punch 7 has adjacent to it a supporting pin 8 upon which the outwardly turned side walls 9 of the blank 10 rest. The 45 top of the blank at 11 is spaced away from the top of the punch 7. The movement of the punch with respect to the die 12 is limited by the pin 13 which is ground off level with the face of the punch. This pin 13 co- 50 operates with the corresponding pin 14 carried by the die supporting member 15. The punch and die are guided relative to one another by the pin 16 and the tubular aperture 17 found respectively in the punch and 55 die. The die 12 has within it a spring pressed pin 18 that is maintained in its out-

ermost position, as shown in the drawing, by the spring 19 within the passage way 20 of the die-supporting member 15. The die 12 is held upon 15 by a pin 21 or threaded member of any desired construction. The pin 18 is limited in the outward movement by the shoulder 22 which abuts against the bottom of the die 12.

Referring again to the punch, it will be 65 seen that as it descends under pressure, the descent will be resisted by the helical spring 23 which surrounds the guiding pin 24 that is loosely fitted into a guiding plate 25 carried by a stationary pin 26 affixed to the 70 punch supporting member 1. It will also be seen that the connection between 5 and 24 at 27 is a flexible one to permit of the lateral movement to which 5 is subjected due to its 75 passage over the cam surface 4 at 6. The punch itself is detachably secured by a threaded member 28 to 5.

In operation, when the punch and die are brought into engagement with one another as in the present instance, the two members 80 approach far enough for the punch and die to have their respective outer surfaces and edges come to a point where their lateral shifting will shear the top 11 of the blank as shown in Figure 2.

If it were not for the spring pressed member 18 holding the top 11 in proper position when this shearing takes place there would be a crinkling or buckling of the blank or it might be disturbed in its position on the 90 punch leading to its being deformed in the shearing or trimming operation. In the present construction the blank is seated firmly upon the pin 8 and is held in its position by a spring pressed member 18 so that the 95 shearing can be effected neatly and quickly without warping or disturbing the blank. In this instance, it is desired to secure a cylindrical member with open ends.

While I have shown and described certain 100 features as constituting my invention, it will be understood that parts have been shown for purposes of illustration only, and that I do not desire to be limited to such details, as obvious modifications will occur to a person 105 skilled in the art.

Having thus fully described my invention, what I claim as new and desire to secure by Letters Patent, is:—

1. In combination, a punch adapted to 110 have lateral and vertical movement relative to a die, a die, means in said die adjacent the

wall thereof having its outer end flush with the face of the die adapted to make contact with a blank on the punch, yielding means for maintaining said member in its outermost position and embracing the blank between it and the punch, means on said punch for supporting a portion of the blank adjacent the die, whereby a blank may be trimmed without deforming it.

10 2. In combination, a punch adapted to have lateral and vertical movement relative to a die, a die, means in said die adjacent the wall thereof having its outer end flush

with the face of the die adapted to make contact with a blank on the punch, yielding means for maintaining said member in its outermost position and embracing the blank between it and the punch, means on said punch for supporting a portion of the blank adjacent the die, and means for limiting the relative movement toward one another of said punch and die, whereby a blank may be trimmed without deforming it.

In testimony whereof, I affix my signature.

CHARLES M. BREHM.
